CLAIM

The ornamental design for a beverage container, as shown and described.

DESCRIPTION

FIG. 1 is a perspective view of a beverage container of my new design;

FIG. 2 is a front elevational view of the beverage container; FIG. 3 is a rear elevational view of the beverage container; FIG. 4 is a left side elevational view of the beverage container, the right side elevational view being a mirror image thereof;

FIG. 5 is a top plan view of the beverage container; and, FIG. 6 is a bottom plan view of the beverage container. The feature shown in broken lines in the drawings forms no part of the claimed design.

The broken lines depict portions of the device that form no part of the claim.
